UNITED STATES PATENT OFFICE.

NATHANIEL C. ROSS, OF FORT WAYNE, INDIANA.

TOILET-SEAT PROTECTOR.

Application filed July 16, 1927. Serial No. 206,362.

The invention relates to protectors for toilet seats and its object is to provide an efficient sanitary article which may be readily applied to a seat and which will thoroughly protect the occupant, and which may be folded into a small package for dispensing or transportation.

An embodiment of the invention is illustrated in the accompanying drawings in which,

The protector consists of a plurality of sheets of suitable paper 1 secured to a relatively narrow strip of suitable material 2, preferably paper. The sheets overlap somewhat and the strip 2 is secured to one end portion of each sheet only so that the sheets will overlap and will readily slide over each other into the compact form shown in Fig. 4 for insertion into an envelope or other container.

In use the protector is drawn out to its full length and laid on one side of the seat and then drawn around and on the front and onto the other side, so that the article surrounds the seat opening. The strip 2 readily yields laterally so that the sheets may be twisted laterally to fully contact with the seat about the opening thereof.

The paper sheets may be paraffined or formed of suitable paper that will be water proof and thereby prevent all foreign matter from passing through them. The paper may be treated with antiseptic material also.

As much of the protector may be used as is desired, the remainder being torn off by severing the strip. The paper will readily discharge through the toilet.

The strip between each two sheets readily folds so that the sheets may be fully overlapped into a small package suitable for insertion in an envelope, in which condition it is most convenient to carry or dispense.

What I claim is:

1. A seat protector consisting of a plurality of overlapped sheets of paper narrower than the sheets secured to a strip of paper, the strip being secured to a portion of each sheet only.

2. A toilet seat protector consisting of a relatively narrow strip of paper and a plurality of overlapped sheets of paper wider than the strip secured at points adjacent to their middle portions to the strip, the strip being such that the sheets may be twisted laterally to cause the protector to surround the seat opening.

3. A toilet seat protector consisting of a narrow strip of paper and a plurality of overlapped sheets of paper secured to the strip each sheet extending laterally beyond the opposite side edges of the strip, the strip being foldable transversely between each two sheets to permit said sheets to stack one upon another in a package and said strip permitting the sheets to be twisted laterally to conform to the curvature of the seat opening.

In witness whereof I have hereunto signed my name this 14th day of July, 1927.
